GEORGE HENRY MAYNARD, OF BERLIN, MASSACHUSETTS.

Design No. 4,424, dated October 18, 1870.

DESIGN FOR SHOES.

The Schedule referred to in these Letters Patent and making part of the same

I, GEORGE HENRY MAYNARD, of Berlin, in the county of Worcester and State of Massachusetts, have invented and produced a new and original Design for Boots and Shoes, of which the following is a specification.

On the drawing—

The nature of my design is fully represented in the accompanying drawing, to which reference is made.

I claim as my invention—

The design for a boot and shoe, as herein shown.
GEORGE HENRY MAYNARD. [L. S.]
